United States Patent Office

Des. 185,854
Patented Aug. 11, 1959

185,854

TESTER CABINET

Richard H. Van Den Berg, Milwaukee, Wis., assignor to
U-Test-M Mfg. Co., Inc., Milwaukee, Wis., a corpora-
tion of Wisconsin

Application December 2, 1958, Serial No. 53,627

Term of patent 14 years

(Cl. D26—1)

FIG. 1

FIG. 2

FIG. 3

FIG. 4

FIG. 5

FIG. 6

Fig. 1 is a front elevational view of a tester cabinet showing my new design;

Fig. 2 is a side elevational view the opposite side being a substantially mirror image thereof;

Fig. 3 is a top plan view;

Fig. 4 is a fragmentary rear elevational view, showing the upper portion of the cabinet, the lower conventional portion being broken away for convenience in illustration;

Fig. 5 is a perspective view; and

Fig. 6 is a fragmentary cross sectional view thereof taken on the line 6-6 of Fig. 5.

I claim:

The ornamental design for a tester cabinet, as shown and described.
